ATTORNEY:

UNITED STATES PATENT OFFICE.

GILBERT D. EMERSON, OF PHILADELPHIA, PENNSYLVANIA.

TEMPORARY BINDER.

SPECIFICATION forming part of Letters Patent No. 764,284, dated July 5, 1904.

Application filed August 20, 1902. Serial No. 120,288. (No model.)

To all whom it may concern:

Be it known that I, GILBERT D. EMERSON, a citizen of the United States, residing in the city of Philadelphia, county of Philadelphia, 5 State of Pennsylvania, have invented certain new and useful Improvements in Temporary Binders, of which the following is a full, clear, and exact description, reference being had to the accompanying drawings, which form a 10 part of this specification.

My invention relates to certain improvements in temporary binders for use in binding magazines, pamphlets, music, and kindred publications; and the object of my said 15 invention is to produce a simple and efficient device of this character which is composed of two parts, strong and durable, and which may be very easily manipulated to insert or remove the publications to be bound.

With this end in view my invention consists of a temporary binder having certain details of construction, such as will be herein-after fully described, and particularly pointed out in the claims made hereto.

Referring to the accompanying drawings, in which similar numerals of reference are used to designate similar parts, Figure 1 is a plan view of a binder constructed in accordance with my invention, a portion of the 30 leaves of the binder and of the periodical being broken away for convenience. Fig. 2 is an end view of Fig. 1. Fig. 3 is a detail longitudinal section through a portion of the binder, showing the locking mechanism for the binding-bar. Fig. 4 is a detail perspective of the slide-block which holds and locks the binding-rod in position. Fig. 5 is a detail plan view in section, illustrating the slide-block in position when the bar is locked. Fig. 40 6 is a detail longitudinal section showing the hinged end of the binding-rod.

In carrying out my invention I provide a back of the usual book form, having the curved section 1 and the two heavy leaves 2 and 3, which are hinged or flexibly connected to the section 1. At one end of the concave section 1 is a fixed block 4, having a slot or groove 5, in which is pivoted or hinged one end of the binding-rod 6. The other end of 50 the binding-rod is provided with a notch 7

adjacent to its end, which is engaged by a detent 8, formed on the under side of a slide-block 9, which is mounted in this end of the section 1 of the back. This slide-block 9 has side ledges 10, which work in the grooves 11, 55 formed in the end of the back section 1. On the inner end of these ledges 10 are the side projections 12, which operate in the grooves 11 and serve to prevent the block 9 from being removed entirely out of the groove, and 60 thus prevent of its being lost or misplaced.

In operation when it is desired to insert a magazine or other pamphlet into the binder the slide 9 is moved outwardly after depressing the notched end of the binding-rod 6, thus 65 releasing the said rod, so that it may be moved outwardly from its hinged end and the magazine placed in position, after which the binding-rod is pulled down in position and held at its notched end until the slide-block 9 is 70 moved back into normal position and its detent 8, carried on the under side of said block, has engaged the notch 7, and thereby firmly locked the binding-rod in position, thus firmly holding the magazine to the binder. The 75 spring in the rod 6 serves to keep it closely in contact with the block 9, and at the same time this spring-pressure causes the ledges on the said block to bind in the grooves 11, and thus prevent the said block from being easily removed. When it is desired to remove the magazine, the end of the rod 6 is pressed down with the finger, and the slide can then be 80 readily moved outwardly and the end of the rod released, as will be readily understood. 85

Minor changes in details of construction may be made without departing from the spirit and scope of my invention, and equivalent elements may be used, as may be the choice of one skilled in the art, to accomplish the same 90 result.

Having thus described my said invention, what I claim, and desire to protect by Letters Patent, is—

1. In a temporary binder, the combination 95 with the back, of a binding-rod hinged at one end to the back, a slidable block adjacent the other end and adapted to move longitudinally of said back, and engaging means carried respectively by the under side of said block and 100

the free end of said rod, which hold the rod beneath said block and prevent longitudinal movement of said block when in operative position.

- 5 2. The combination, in a temporary binder, of a concave back, sides flexibly connected therewith, a binding-rod hinged at one end to the back adjacent one end thereof, a grooved bearing formed on the other end of said back, 10 a slidable block adapted to said bearing so as to move longitudinally, means for limiting

the sliding movement of said slidable block, and a catch having coacting parts, formed respectively on the under side of said slidable block and in the free end of the binding-rod. 15

In witness whereof I have hereunto set my hand this 30th day of July, A. D. 1902.

GILBERT D. EMERSON.

CHAS. K. BENNETT.

Correction in Letters Patent No. 764,284.

It is hereby certified that in Letters Patent No. 764,284, granted July 5, 1904, upon the application of Gilbert D. Emerson, of Philadelphia, Pennsylvania, for an improvement in "Temporary Binders," an error appears in the printed specification requiring correction, as follows: In line 17, page 1, the word "two" should read *few*; and that the said Letters Patent should be read with this correction therein that the same may conform to the record of the case in the Patent Office.

Signed and sealed this 19th day of July, A. D., 1904.

[SEAL.]

E. B. MOORE,
Acting Commissioner of Patents.
